CLAIM

The ornamental design for a telephone adapter for a cellphone-internet communication system, as shown and described.

DESCRIPTION

FIG. 1 is a perspective view from the top, front and left side of a telephone adapter for a cellphone-internet communication system showing my new design;

FIG. 2 is an elevational view from the right side thereof;

FIG. 3 is an elevational view from the front thereof;

FIG. 4 is an elevational view from the rear thereof;

FIG. 5 is a plan view from the top thereof; and

FIG. 6 is a plan view from the bottom thereof.

FIG. 7 is a perspective view from the top, front and left side of a second embodiment thereof;

FIG. 8 is an elevational view from the right side on the embodiment shown in FIG. 7;

FIG. 9 is an elevational view from the front of the embodiment shown in FIG. 7;

FIG. 10 is an elevational view from the rear of the embodiment shown in FIG. 7;

FIG. 11 is a plan view from the top of the embodiment shown in FIG. 7; and,

FIG. 12 is a plan view from the bottom of the embodiment shown in FIG. 7.
